UNITED STATES PATENT OFFICE.

SIDNEY S. WHELAN, OF WESTBURY, NEW YORK.

COLLAPSIBLE CONTAINER.

Application filed July 6, 1923. Serial No. 648,810.

This invention relates to containers. More specifically the invention relates to collapsible containers and has for one of its objects to provide a sealed collapsible container adapted to contain tobacco and provided with a manually operable means for opening the container. Other objects and advantages will appear as the invention is hereinafter disclosed.

10 Referring to the drawings which illustrate what I consider a preferred form of the invention:

Fig. 1 is an elevation of a container.

15 Fig. 2 is a vertical section on the line 2—2 of Fig. 1.

Fig. 3 is a detail view of the opening means.

20 Fig. 4 is a detail elevation of the upper end of the container before completion of the folding.

25 Fig. 5 is an elevation of the upper end of the container shown in Fig. 1, the view being taken from the opposite side and illustrating the position of parts during the opening operation.

While the container may be made in other shapes and of other materials I prefer at present to construct it in the form of a tube—preferably a seamless tube 10 of foil, such as tin foil, having a closed bottom 11. The upper end 12 of the container 10 is shown closed or sealed by flattening it (see Fig. 2). If desirable, the upper end of the container may be cemented in addition to being closed by flattening.

30 It will be understood, of course, that the tobacco or other material will be placed in the container before the closing or sealing operation. The container is provided with 40 means for rupturing and opening the upper end to render the contents accessible. While this means may consist of wire or similar device within the scope of the invention as hereinafter defined in certain of the claims, I prefer at present to employ the device shown in Fig. 3 and which I shall now proceed to describe.

45 The container-opening device is preferably constructed of sheet metal, such as tin, and comprises a knife or cutting portion 14 having disc-like ends 13, each shown provided with an aperture or opening 15. After the container 10 is closed or sealed as described above and shown in Fig. 4, it is folded around the opening device 14, as

shown in Fig. 2, and the folds pressed together to form the finished article illustrated in Fig. 1. The container so formed is especially adapted to contain and preserve tobacco since it is effectively sealed and impervious to moisture, vermin, etc. The container may be readily opened as follows.

One of the ends 13 of the opening device is grasped by the hand, or a suitable tool such as a match stem inserted through its opening 15, and the said end pulled upwardly; i. e., away from the container 10 in a direction longitudinally of the container. During this operation the upper edge of the cutting portion 14 acts as a cutting or shearing edge and cuts through the container on a plane containing the device 13—14 (see Fig. 5); i. e., on the line 16 indicated in Fig. 4. In this manner the upper, sealed end of the container is completely severed from the remainder thereof and the contents of the container are readily accessible. In view of the material of which the container is constructed, the now open mouth thereof may be readily bent or creased to form a pouring spout or trough and the tobacco—assuming that the container is employed to hold tobacco—readily poured into a pipe or cigarette paper. When it is desired to close the opened container, this may readily be effected by pinching or folding the upper end together. As the contents of the container diminish the upper end may be rolled, or folded, or otherwise collapsed so as to decrease the size of the container 50 commensurate with the volume of the remaining contents.

If the portion 14 of the shearing device is constructed of sufficiently thin material its upper or cutting edge (Fig. 5) will be 55 sufficiently sharp to shear through the foil. If this portion 14 is constructed of thick material it may be sharpened at its upper edge to provide a cutting edge.

In employing the word "foil" I mean thin sheet plastic metal such as that commonly employed in tubular containers for tooth paste, shaving cream, etc.

60 In accordance with the provisions of the patent statutes, I have herein described the principle of operation of my invention, together with the apparatus which I now consider to represent the best embodiments thereof, but I desire to have it understood that the apparatus disclosed is only illus- 65

trative and that the invention can be carried out by other means.

What I claim is:—

5 In combination, a substantially tubular normally sealed container constructed of foil and adapted to be collapsed to conform to diminishing volumes of the contents, one end of said container being flattened and

folded upon itself, and a shearing device having a shearing portion enclosed by said flattened and folded end of said container wholly exterior of the container. 10

In testimony whereof I hereto affix my signature.

SIDNEY S. WHELAN.
